UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed May 22, 1922, Serial No. 562,578. Renewed June 18, 1926.

This invention comprehends improvements of general utility in the coking retort oven art, and also comprehends certain improvements especially applicable to coking retort ovens of the well known cross-regenerative type exemplified in Letters Patent of the United States to H. Koppers, No. 818,033, dated April 17, 1906, and in my prior patent for a coking retort oven No. 1,374,546, dated April 12, 1921.

The invention has for objects the provision of a coking retort oven having, as important characteristics: a flue construction involving the location of the horizontal or bus flue, which connects the tops of the vertical flame flues with each other, above the top of the retort or coking chamber contiguous to the heating wall containing the vertical flues, with the result that the upper part of the retort is not exposed to the effect of the hot gases passing through the horizontal or bus flue and over-coking of the upper part of the coal charge and destruction of the distillate gases which collect in the upper region of the retort are avoided. As a further feature to secure the above mentioned improvement the invention provides insulation in that portion of the heating wall which surrounds the ducts connecting the vertical flues with the horizontal flue and also provides insulation between the sides of the horizontal flue and the top structure of the battery that is located directly above the retorts, so that overheating in the upper regions of any of the retorts is avoided.

Inasmuch as the horizontal flues are located entirely above the upper zone of the various retorts, the flame flues may be increased in height, with a corresponding increase in height of the coking chambers so that the latter may be made narrower in width, a development greatly facilitating the coking of high volatile coals, and yet having adequate provision in the horizontal flue for taking care of the increased volume of combustion products, for the reason that the horizontal flue dimensions may be made adequate to such volume, without introducing elements of weakness in the heat-

ing wall construction. The flue construction of the invention is furthermore of great importance in oven batteries fired with extraneously-derived gas, such as producer gas, since the employment of such gas results in an increased volume of combustion products and adequate flue spaces must be provided to collect from the upflow flues and feed to the downflow flues this increased volume of combustion products.

In addition to the general objects recited above, the invention has for further objects such other improvements or advantages in construction and operation as are found to obtain in the structures and devices hereinafter described or claimed.

In the accompanying drawings forming a part of this specification and showing, for purposes of exemplification, a preferred form and manner in which the invention may be embodied and practiced, but without limiting the claimed invention to such illustrative instance or instances:

Figure 1 is a crosswise vertical section through a coke oven battery embodying features above specified and equipped with the improvements of the present invention, the view being taken longitudinally through a heating wall and the communicably connected regenerators, in planes indicated by the line D—D of Fig. 2; and

Fig. 2 is a composite vertical sectional elevation taken longitudinally of the coke oven battery in planes indicated by the lines A—A, B—B and C—C of Fig. 1.

The same characters of reference designate the same parts in each of the several views of the drawings.

In the embodiment illustrated in the drawings, the invention is incorporated in a combination coke oven battery, i. e., a battery having provision for being operated either with a relatively lean extraneously-derived gas, such as producer gas, for fuel, or with the coke oven gas derived from the distillation of the coal in the retorts of the battery. The combination oven principle is described and claimed in the prior Letters Patent of the United States of H. Koppers, No. 1,026,169, for "Retort-oven for producing

gas and coke," dated May 14, 1912. For convenience, the present description will be confined to the present illustrated embodiment of the invention in such a combination oven battery; the novel features and improvements made by the invention are, however, susceptible of other applications, such, for example, as ordinary so-called "coke ovens" employing coke oven gas as the fuel, or ordinary so-called "gas ovens" employing an extraneously-derived gas as the fuel; hence, the invention is not confined in its scope to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11 and a plurality of intermediate crosswise elongated retorts or coking chambers 12. The heating walls 11 form the side walls of the respective coking chambers 12, as shown more particularly in Fig. 2, and, in the present instance, are directly supported by the heavy supporting or pillar walls 13 which extend crosswise of the battery and are located, as shown in Fig. 2, beneath the respective heating walls 11. These pillar walls, together with other walls, hereinafter described, collectively form the main support for the entire superstructure of the retort oven battery and are themselves supported upon a flat mat or platform which constitutes the sub-foundation on which the entire battery rests. The coal to be coked is charged into the several coking chambers or ovens through charging holes 14 located in the top 15 of the oven battery and positioned directly above the ovens or chambers 12, as indicated by dotted lines in Fig. 2. These charging holes 14 are equipped with the usual removable covers, which are removable during charging of the individual retorts or coking chambers and are placed in position to close the tops of such coking chambers during the entire coking or distilling operation. The gases of distillation pass from the tops of the several coking chambers 12 through the usual gas outlets (not shown) and thence through ascension pipes (not shown) into the usual gas collecting main which carries the distillation products to the by-product recovery apparatus. Heat for coking the charges of coal in the several ovens or chambers 12 is derived from the heating walls 11, which, as before mentioned, extend crosswise of the battery at the sides of the coking chambers. Each heating wall 11 is constituted of a plurality of flame or combustion flues 17. In the present embodiment of the invention, the flame flues of each heating wall are divided

into two groups E and F by the middle lengthwise line L of the retort battery. When the flame flues of all the groups E on one side of the aforesaid line L are operating for upflow, that is to say burning, the flame flues on the opposite side of the said middle lengthwise line L are operating for downflow to permit exhaust of the waste gases, in accordance with the usual practice exemplified in the prior patent to H. Koppers, No. 818,033, hereinbefore mentioned. On reversal of the battery, the upflow flame flues of the groups E become downflow flame flues and the downflow flame flues of the groups F become upflow flame flues.

The crosswise regenerators 18 of the battery are located at a lower level than the aforesaid heating walls 11 and coking chambers 12, and, in the present instance extend in parallelism between the pillar walls 13 and the other heavy supporting walls hereinafter described. Located in the middle lengthwise vertical plane L of the coke oven battery, is a vertical partition 19, as shown in Fig. 1, which partition extends all the way up from the mat of the battery to the bottom of the overlying coking chamber and from one to the other of the pillar walls 13 and the other walls which are between the pillar walls. The regenerators, which are respectively located in series on opposite sides of the battery extend inwardly to said partition 19 and are separated thereby as clearly shown in Fig. 1. If desired, each regenerator 18 may be provided with a vertical partition 20 located substantially midway between the aforesaid partition 19 and the side of the battery.

Each regenerator 18 is a chamber containing open brick work, commonly called checkerwork and indicated at 21, with a distributing sole channel 22 underneath such checkerwork, the channels forming the soles of such chambers and opening up into the checkerwork. The regenerators are heated, in alternation, by the hot combustion products exhausted from the flame or combustion flues herein before mentioned and then impart such heat to the medium that they feed into these flame flues.

In the present embodiment of the invention, a heavy vertical gas-tight supporting wall 22 extends directly beneath each retort or coking chamber in parallelism between each two adjacent heating walls 13. Such supporting walls 22 provide two regenerators located respectively on the opposite sides of such walls 22 and between adjacent pillar walls 13. The other walls 23 also have the function with the pillar walls 13 of supporting the weight of the battery superstructure. This supporting wall construction provides two series of crosswise extending parallel gas-tight load carrying walls

located below the coking chambers and intermediate heating walls, the supporting walls of one series 13 being directly beneath the heating walls and the supporting walls of the other series 23 being directly beneath the coking chambers. The walls 23 which are beneath the coking chambers are constructed and function not as mere partitions commonly employed but as true load carrying 10 gas-tight walls permitting the flow of different media in the checkerwork chambers separated from these walls without leakages from one checkerwork chamber into another and without danger of mixing gases in the 15 checkerwork chambers which must be kept separate in this region of the battery.

The several regenerators on one side of the aforesaid partition 19 comprises a series E' which operate concurrently for flow in 20 one direction and the several regenerators on the other side of said partition 19 comprise a series F' which operate concurrently for flow in the opposite direction. Each regenerator is provided with a series of ducts 24 25 all of which lead respectively to individual flame flues 17 of the same heating wall. As shown in Fig. 2, the regenerators of each series E' or F' are grouped into pairs G separated by the load carrying walls 23 and the 30 ducts 24 of both regenerators of each pair lead respectively to flame flues of the single heating wall that is located above the pillar wall 13 which separates the individual regenerators of each pair. With this construction, each flame flue 17 communicates by 35 a pair of ducts 24 with adjacent separate regenerators.

In the present embodiment of the invention, the reversal in flow through the flame 40 flues 17 on opposite sides of the before mentioned central longitudinal plane L, together with their communicably connected regenerators, takes place transversely of the battery, as has heretofore been a common 45 practice in this art. The reversal of the battery is effected at the end of an operating period determined by practice and by means of any preferred type of reversing mechanism. The function of such reversal is as 50 follows: the regenerators that prior to the reversal operated as inflow regenerators become outflow regenerators, and the outflow operating regenerators become inflow operating regenerators; the upburning series 55 of flame flues switches function with the downflow operating series of flame flues, and the supply of gas is turned off from the previously upburning flues and turned on into the mains of the previously downburning flues.

In accordance with the present invention, the port or duct 25, which communicates with the top of each flame flue 17 for draft and the passage of combustion products 65 from the flue, extends to a horizontal plane

coincident with the top of the adjoining coking chamber 12, as shown in Fig. 2. The ports or ducts 25 of both groups E and F of each heating wall open up into the horizontal or bus flue 26 which is located, as 70 provided by the invention, in the top structure 15 of the battery above the top of the adjoining coking chamber. The horizontal or bus flue 26 is connected with all the flame flues of its corresponding heating wall and 75 permits the waste gases from the upburning flues on one side of the central plane L to exhaust into the downflow flues on the other side of said central plane. By extending the ducts 25 clear to the top of the adjoining coking chambers and by the location of 80 the horizontal flue in the top structure 15 of the battery, the upper regions of the adjoining coking chambers are substantially unexposed to radiation from the hot gases 85 which pass through the horizontal flue 26, and destructive temperatures in such upper regions of the coking chambers are avoided. A further advantage of this construction is that the horizontal flues 26 may 90 be made of dimensions adequate to accommodate an increased volume of combustion products, without affecting the desired thickness of the upper portion of the heating wall. The maximum diameter of each of 95 the ducts 25 transversely of the coking chambers 12 is, as shown on the drawing, a minor fraction of the maximum diameter of the vertical combustion flues 17 transversely of the coking chambers 12, and the 100 ducts 25 are also vertically elongated for a distance substantially as great as the minimum height of the horizontal flues 26, and are separated throughout their vertical dimensions from the top portions of the adjacent coking chambers 12 by walls that are 105 substantially thicker than the portions of the combustion flue walls 11 facing the coking chambers at the tops of the combustion flues. The ducts 25 are also of substantially 110 uniform horizontal cross-sectional area from the levels of the tops of the coking chambers 12 down to the tops of the combustion flues 17. In order further to protect the upper regions of the retort 12 from the hot 115 gases within the ducts 25 and horizontal flues 26, a vertical layer 27 of any suitable insulating material is interposed in the heating wall structure on each side of each series 120 of ducts 25, between such series of ducts and the side faces of the upper region of the heating wall. Vertical insulating layers 28 of insulating material may also be provided along the opposite sides of the horizontal 125 bus flues 26 to protect from the hot gases within the bus flues the top of the battery which is located directly above the top of the retort or coking chamber. Preferably the insulating layers 27 and 28 extend substan- 130

tially coextensively with the series of ducts 25 and the horizontal flues 26.

The draft through the ports or ducts 25 may be regulated by means of the usual 5 movable dampers or sliding bricks 29, positioned in the ordinary way in the bottoms of the horizontal flues 26 and adapted to be reached by access flues 30. These access flues extend from the top of the horizontal flues 10 26 in each heating wall through the top 15 of the battery, there being an access flue positioned over each flame or combustion flue of each heating wall.

Extending crosswise of the battery in each 15 pillar wall 13 and located beneath the heating wall 11 thereabove, is a pair of gas-supply channels 31. These channels 31 extend from the opposite sides of the battery inwardly to the central longitudinal plane L, 20 as fully described in my said prior Patent No. 1,374,546 and are communicably connected with the individual flues 17 by means of the usual ducts within which are disposed the usual gas nozzles. The channels 25 31 are for the purpose of supplying coke oven gas to the several flame flues on one side of the central plane L, when the flues are burning on that side and, after reversal, to the several flame flues on the opposite side of the before mentioned central plane L. The supply of coke oven gas to the respective channels 31 is derived from coke oven gas mains of the usual type and are respectively located on the opposite sides of 30 the battery and extend longitudinally therewith. Suitable means is provided for admitting or cutting off the supply of gas with respect to the channels of each side of the battery, it being understood that the supply 35 is maintained on one side of the battery while cut off from the other.

For operating the battery alternately with the use of a special generator gas, such as producer gas, one regenerator of each pair 45 G may be optionally connected with a producer gas main, by mechanism such as is disclosed in my prior Letters Patent of the United States for a Coking retort oven, No. 1,416,322, issued May 16, 1922, so that the 50 producer gas may be directed into the inflow regenerators P and conveyed through these regenerators into burning flame flues 17.

The operation of the battery, when employing a special generator gas, such as ordinary producer gas, is as follows: the supply 55 of coke oven gas to the coke oven of all of the gas channels 31 is cut off. A supply of producer gas is permitted to flow into the 60 the inflow regenerators P, and passing through said regenerators, the producer gas is preheated before being delivered into the burning flame flues. During the inflow of producer gas through such regenerators P, 65 waste gas from the downburning flues is

flowing out through the regenerators of the series on the opposite side of the battery, so that the latter operate as waste gas regenerators W. In the other regenerators A of the inflow series, inflow of air is maintained and passing upwardly through such regenerators, the air finally enters the burning flame flues to support the combustion of the producer gas that is delivered thereto by the 70 gas regenerators P. On reversal of the flow, the inflow operating regenerators become 75 outflow regenerators and concurrently the outflow operating regenerators become inflow regenerators.

In operating the battery with coke oven 80 gas in the ordinary manner, the supply of producer gas to the regenerators P is shut off and air is permitted to flow into such regenerators in place of the producer gas, so that all of the regenerators of the inflow 85 series operate for inflow of air. During coke oven gas operation, a supply of coke oven gas is maintained in the channels 31 which feed the upburning flues. The reversing mechanism is operated at each reversal to 90 place all of the inflow operating regenerators in communication with the outer air and concurrently all of the outflow operating regenerators in communication with the exhaust.

The invention as hereinabove set forth is embodied in a particular form of construction, but may be variously embodied within the scope of the claims hereinafter made.

I claim:

1. A coking retort oven comprising, in combination: a series of alternate substantially parallel horizontal coking chambers and heating walls therefor arranged side-by-side in a substantially horizontal row, each of said heating walls comprising vertical combustion flues; horizontal flues in the top structure above the coking chambers and the heating walls and communicably connected with a plurality of combustion flues of the heating walls respectively by duct means extending as high as the tops of the coking chambers adjoining said heating walls; insulating means interposed between said duct means and the opposite side faces of the heating walls; and insulating means extending along the opposite sides of each horizontal flue to protect from the hot gases in each horizontal flue that region of the top structure which is located directly above each coking chamber; substantially as specified.

2. A coking retort oven comprising, in combination: a series of alternate substantially parallel horizontal coking chambers and heating walls therefor arranged side-by-side in a substantially horizontal row, each of said heating walls comprising vertical combustion flues; horizontal flues in the top structure above the coking chambers and

- the heating walls and communicably connected with a plurality of combustion flues of the heating walls respectively by duct means extending as high as the tops of the 5 coking chambers adjoining said heating walls; and insulating means interposed between said duct means and the opposite side faces of the heating walls; substantially as specified.
- 10 3. A coking retort oven comprising, in combination: a series of alternate substantially parallel horizontal coking chambers and heating walls therefor arranged side-by-side in a substantially horizontal row, each 15 of said heating walls comprising vertical combustion flues; horizontal flues in the top structure above the coking chambers and the heating walls and communicably connected with a plurality of combustion flues 20 of the heating walls respectively by duct means extending as high as the tops of the coking chambers adjoining said heating walls; and insulating means extending along the opposite sides of each horizontal flue to 25 protect from the hot gases in each horizontal flue that region of the top structure which is located directly above each coking chamber; substantially as specified.
4. A coking retort oven comprising, in combination: a series of alternate substantially parallel horizontal coking chambers and heating walls therefor arranged side-by-side in a substantially horizontal row, each 30 of said heating walls comprising vertical combustion flues; horizontal flues extending into the top structure that is above the coking chambers and the heating walls and communicably connected by duct means with a plurality of combustion flues of the heating 35 walls, respectively, for passage of combustion products to and from said flues in alternation; insulating means interposed between said duct means and the opposite side faces of the heating walls; and insulating means 40 extending along the opposite sides of each horizontal flue to protect from the hot gases in each horizontal flue that region of the top structure which is located directly above each coking chamber; substantially as specified.
- 45 5. A coking retort oven having a series of alternate substantially parallel horizontal coking chambers and heating walls therefor arranged side-by-side in a substantially horizontal row, each of said heating walls comprising vertical combustion flues and each of 50 said coking chambers extending a considerable distance above the levels of the tops of said combustion flues in the heating walls contiguous thereto, combined with horizontal flues located substantially entirely above the levels of the tops of the coking chambers and also above the levels of the tops of said vertical combustion flues and each of said 55 horizontal flues being communicably connected with a plurality of combustion flues of one of said heating walls, by ducts for passage of combustion products to and from said vertical combustion flues in alternation, said ducts having their maximum diameter transversely of said coking chambers a minor fraction of the maximum diameter of the vertical combustion flues transversely of said coking chambers and also being disposed above the levels of the tops of the vertical combustion flues and below the levels 60 of the bottoms of said horizontal flues and communicating with the combustion flues at the tops thereof and with the horizontal flues at the bottoms thereof, and being both vertically elongated for a distance substantially as great as the minimum height of the horizontal flues and separated throughout their vertical dimensions from the top portions of the adjacent coking chambers by walls that are substantially thicker than the portions of the combustion flue walls facing the coking chambers at the tops of the combustion flues.
6. A coking retort oven having a series of alternate substantially parallel horizontal coking chambers and heating walls therefor arranged side-by-side in a substantially horizontal row, each of said heating walls comprising vertical combustion flues and each of 65 said coking chambers extending above the levels of the tops of said vertical combustion flues in the heating walls contiguous thereto, combined with horizontal flues located substantially above the levels of the tops of the coking chambers and also above the levels of the tops of said vertical combustion flues and each of said horizontal flues being communicably connected with a plurality of the combustion flues of one of said heating walls, for passage of combustion products to and from said combustion flues in alternation, by ducts which lie above the levels of the tops of said combustion flues and below the levels of the bottoms of said horizontal flues and communicate with the combustion flues at the tops thereof and with the horizontal flues at the bottoms thereof; said ducts being both vertically elongated and of substantially uniform horizontal cross-sectional area from the levels of the tops of the coking 70 chambers adjoining said heating walls down to the levels of the tops of the combustion flues and also separated throughout their vertical dimensions from the top portions of the adjacent coking chambers by walls that are substantially thicker than the portions of the combustion flue walls facing the coking chambers at the tops of the combustion flues.
- 75 7. A coking retort oven having a series of alternate substantially parallel horizontal coking chambers and heating walls therefor arranged side-by-side in a substantially horizontal row, each of said heating walls comprising vertical combustion flues and each of 80 said coking chambers extending a considerable distance above the levels of the tops of said combustion flues in the heating walls contiguous thereto, combined with horizontal flues located substantially entirely above the levels of the tops of the coking chambers and also above the levels of the tops of said vertical combustion flues and each of said horizontal flues being communicably connected with a plurality of the combustion flues of one of said heating walls, for passage of combustion products to and from said combustion flues in alternation, by ducts which lie above the levels of the tops of said combustion flues and below the levels of the bottoms of said horizontal flues and communicate with the combustion flues at the tops thereof and with the horizontal flues at the bottoms thereof; said ducts being both vertically elongated and of substantially uniform horizontal cross-sectional area from the levels of the tops of the coking 85 chambers adjoining said heating walls down to the levels of the tops of the combustion flues and also separated throughout their vertical dimensions from the top portions of the adjacent coking chambers by walls that are substantially thicker than the portions of the combustion flue walls facing the coking chambers at the tops of the combustion flues.
- 90 8. A coking retort oven having a series of alternate substantially parallel horizontal coking chambers and heating walls therefor arranged side-by-side in a substantially horizontal row, each of said heating walls comprising vertical combustion flues and each of 95 said coking chambers extending a considerable distance above the levels of the tops of said combustion flues in the heating walls contiguous thereto, combined with horizontal flues located substantially entirely above the levels of the tops of the coking chambers and also above the levels of the tops of said vertical combustion flues and each of said horizontal flues being communicably connected with a plurality of the combustion flues of one of said heating walls, for passage of combustion products to and from said combustion flues in alternation, by ducts which lie above the levels of the tops of said combustion flues and below the levels of the bottoms of said horizontal flues and communicate with the combustion flues at the tops thereof and with the horizontal flues at the bottoms thereof; said ducts being both vertically elongated and of substantially uniform horizontal cross-sectional area from the levels of the tops of the coking 100 chambers adjoining said heating walls down to the levels of the tops of the combustion flues and also separated throughout their vertical dimensions from the top portions of the adjacent coking chambers by walls that are substantially thicker than the portions of the combustion flue walls facing the coking chambers at the tops of the combustion flues.
- 105 9. A coking retort oven having a series of alternate substantially parallel horizontal coking chambers and heating walls therefor arranged side-by-side in a substantially horizontal row, each of said heating walls comprising vertical combustion flues and each of 110 said coking chambers extending a considerable distance above the levels of the tops of said combustion flues in the heating walls contiguous thereto, combined with horizontal flues located substantially entirely above the levels of the tops of the coking chambers and also above the levels of the tops of said vertical combustion flues and each of said horizontal flues being communicably connected with a plurality of the combustion flues of one of said heating walls, for passage of combustion products to and from said combustion flues in alternation, by ducts which lie above the levels of the tops of said combustion flues and below the levels of the bottoms of said horizontal flues and communicate with the combustion flues at the tops thereof and with the horizontal flues at the bottoms thereof; said ducts being both vertically elongated and of substantially uniform horizontal cross-sectional area from the levels of the tops of the coking 115 chambers adjoining said heating walls down to the levels of the tops of the combustion flues and also separated throughout their vertical dimensions from the top portions of the adjacent coking chambers by walls that are substantially thicker than the portions of the combustion flue walls facing the coking chambers at the tops of the combustion flues.
- 120 10. A coking retort oven having a series of alternate substantially parallel horizontal coking chambers and heating walls therefor arranged side-by-side in a substantially horizontal row, each of said heating walls comprising vertical combustion flues and each of 125 said coking chambers extending a considerable distance above the levels of the tops of said combustion flues in the heating walls contiguous thereto, combined with horizontal flues located substantially entirely above the levels of the tops of the coking chambers and also above the levels of the tops of said vertical combustion flues and each of said horizontal flues being communicably connected with a plurality of the combustion flues of one of said heating walls, for passage of combustion products to and from said combustion flues in alternation, by ducts which lie above the levels of the tops of said combustion flues and below the levels of the bottoms of said horizontal flues and communicate with the combustion flues at the tops thereof and with the horizontal flues at the bottoms thereof; said ducts being both vertically elongated and of substantially uniform horizontal cross-sectional area from the levels of the tops of the coking chambers adjoining said heating walls down to the levels of the tops of the combustion flues and also separated throughout their vertical dimensions from the top portions of the adjacent coking chambers by walls that are substantially thicker than the portions of the combustion flue walls facing the coking chambers at the tops of the combustion flues.
